(57) **CLAIM**

The ornamental design for an aboveground piping system, as shown and described.

DESCRIPTION

FIG. 1 is a top perspective view of my aboveground piping system.

FIG. 2 is a top partial view of the system of FIG. 1 with a section of the lid portion removed.

FIG. 3 is a bottom partial view of the system of FIG. 1.

FIG. 4 is a right side partial view of the system of FIG. 1.

FIG. 5 is a left side view of the system of FIG. 1, with a section of the system removed.

FIG. 6 is a front end view of the system of FIG. 1; and,

FIG. 7 is a rear view of the system of FIG. 1, with a section of the lid portion removed.

A portion of the aboveground piping system has been shown broken away in FIGS. 2 through 5 for convenience of illustration so that the views might be sufficiently enlarged to illustrate details of the design.
